UNITED STATES PATENT OFFICE

162,142

COMBINED TOPPER AND COAT

Joseph Feldman, New York, N. Y.

Application December 8, 1949, Serial No. 6,503

Term of patent 3½ years

(Cl. D3—4)

To all whom it may concern:

Be it known that I, Joseph Feldman, a citizen of the United States of America, residing in New York city, county of New York, and State of New York, have invented a new, original and ornamental Design for a Combined Topper and Coat, of which the following is a specification, reference being had to the accompanying drawing, forming part thereof, wherein,

Figure 1 is a front elevational view of a combined topper and coat showing my new design.

Figure 2 is a rear elevational view of the combined topper and coat.

Figure 3 is a view similar to Figure 1, showing the topper and coat members in partly detached position.

Figure 4 is a front elevational view showing the topper member completely detached from the coat member.

I claim:

The ornamental design for a combined topper and coat, substantially as shown.

JOSEPH FELDMAN.
